UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A HANDLE FOR SPOONS, FORKS, OR SIMILAR ARTICLES.

SPECIFICATION forming part of Design No. 33,457, dated October 30, 1900.

Application filed October 3, 1900. Serial No. 31,933. Term of patent 7 years.

To all whom it may concern:

Be it known that I, WILLIAM C. CODMAN, a subject of the Queen of Great Britain, residing at Providence, in the county of Providence and State of Rhode Island, have invented and produced a new and original Design for the Handle of a Spoon, Fork, or Similar Article, of which the following is a specification, reference being had to the accompanying drawings, forming part thereof.

Figure 1 is a plan view of the front or obverse side, and Fig. 2 is a view of the reverse side, of the handle. Fig. 3 is a sectional view on the line X X of Fig. 1.

15 The connection of the handle with the bowl of a spoon is shown in the drawings in solid lines, and the connection of the handle with the fork in broken lines.

As shown in the drawings, the leading and 20 material feature of my design consists of the raised beads extending between two parallel fillets along the margin of the handle and terminating into scrolls at their ends. The scrolls on the obverse side of the handle are 25 ornamented by foliations. The upper end of the handle has a crested shell ornament

against which the scrolled ends of the marginal beads abut. The scrolls at the opposite ends of the marginal beads turn inward and inclose the convex surface of the escutcheon-panel of the handle. The margin of the neck of the handle is ornamented by two inwardly-curved beads, and the stem of the handle has two beads extending from inwardly-curved scrolls along the margin of the stem 35 and abutting on the foliated scrolls on the margin of the end of the handle connecting with the article with which the handle is connected.

Having thus described my invention, what 40 I claim as new, and desire to secure by Letters Patent, is—

The design for the handle of a spoon, fork or similar article, as herein shown and described.

In testimony whereof I have signed my name to this specification in the presence of two subscribing witnesses.

45 WILLIAM C. CODMAN.
